UNITED STATES PATENT OFFICE

2,439,596

AIR FILTER FOR POLISHING MACHINES

Stephen A. Crosby, Chicago, Ill., assignor to Sterling Tool Products Company, a corporation of Illinois

Application October 2, 1946, Serial No. 700,785

2 Claims. (Cl. 51—170)

1

This invention relates to polishing machines and more particularly to small power driven sanders for use on various structural materials.

The primary object of the invention is to provide an improved means for filtering the air which is sucked into the machine to cool the driving motor.

The invention is illustrated in a preferred embodiment in the accompanying drawings, in which—

Figure 1 is a fragmentary side elevational view, of a polishing machine embodying the invention; Fig. 2 is a fragmentary front elevational view of the door to the air inlet; Fig. 3 is a front elevational view of the replaceable filter screen; Fig. 4 is a sectional view of the door, taken as indicated at line 4—4 of Fig. 2; and Fig. 5, is a fragmentary sectional view, taken as indicated at line 5—5 of Fig. 3.

The machine is generally similar to the one shown in my Patent No. 2,395,537, dated February 26, 1946. A rubbing pad 6 is supported beneath the housing frame 1 and is driven with an orbital movement, at high speed, by a vertically disposed electric motor within the housing. A small fan, not shown, draws air through an inlet opening at the front of the machine and discharges it through slots 8 provided at the top of the machine, as shown in my Patent No. 2,395,537. A door frame 9 is provided in the front of the housing and is of substantially rectangular form. In this frame is seated a filter panel 10 that is held in position by a specially designed door 11 which is the novel feature of the present invention. The filter panel is formed of a thin porous fibrous sheet held between two metal wire screens which are held in position by a marginal binding 12. Preferably the screen is provided with a small tab 13, to facilitate its removal from the door frame for cleaning or replacement.

The door 11 is hinged below the frame on a pintle 14, and a torsion spring 15 is provided to urge the door upwardly into closed position. As shown in Fig. 4, the door 11 is U-shaped in cross-section, and tapers downwardly and inwardly from an upper opening 16 towards the bottom portion of the filter panel. The side portions 17 of the door are adapted to engage the marginal portions of the panel and hold it in position, so that all of the air entering the housing must pass through the panel.

It will be noted that by this construction of the

2

door, the air enters the inlet portion of the housing through the upper portion of the door, and this arrangement has several important advantages over the grille type door shown in my earlier patent. When the machine is used for sanding, there is usually a considerable amount of fine dust near the rubbing pad, and some of this will be quickly sucked into the filter so as to clog up its lower portion after being operated for a few hours. In the present machine, the incoming cool air is drawn from a stratum considerably above the one that is heavily laden with dust, and as a result the filter may be used for a much longer period without requiring cleaning or replacement. The shape of the door also serves to direct the incoming air to all portions of the face of the filter panel, and it has been found that better circulation is obtained, as the motor actually runs cooler than with the original design.

The foregoing detailed description is given for clearness of understanding only, and no unnecessary limitations should be understood therefrom, for some modifications will be obvious to those skilled in the art.

25 I claim:

1. A motor driven rubbing machine comprising: a rubbing pad; a housing containing a motor for driving said pad, said motor having an air-circulating fan; an air inlet to said fan in the front of said housing including a door frame; an air outlet to the housing above the fan; a filter screen adapted to fit into said frame; and a door hinged to said frame so as to hold said screen in the door frame, said door having its body portion spaced from the frame and provided with an opening at its top portion to admit incoming air downwardly to the face of said screen.

2. Apparatus as specified in claim 1, in which the hinge is at the bottom of the door and said door is U-shaped in cross section with its body portion curved downwardly and inwardly towards said hinge.

STEPHEN A. CROSBY.
